UNITED STATES PATENT OFFICE.

HARRY C. TILLOTSON, OF CHICAGO, ILLINOIS, ASSIGNOR TO KNIGHT AMERICAN PATENTS COMPANY, OF CHICAGO, ILLINOIS, A CORPORATION OF ILLINOIS.

EXPLOSION-ENGINE.

1,238,222.

Specification of Letters Patent. Patented Aug. 28, 1917.

Application filed December 17, 1909, Serial No. 533,600. Renewed December 8, 1915. Serial No. 65,830.

To all whom it may concern:

Be it known that I, HARRY C. TILLOTSON, a citizen of the United States, residing at Chicago, in the county of Cook and State 5 of Illinois, have invented a certain new and useful Improvement in Explosion-Engines, of which the following is a full, clear, concise, and exact description, reference being had to the accompanying drawings, forming 10 a part of this specification.

My invention relates to explosion engines and is particularly directed to a novel form of valve in the operation of which principles, not heretofore employed in motor devices of this type, are involved. Not only is the inherent construction of the valve of my invention novel and more efficient than valve constructions of the prior art, but its arrangement relative to the other parts of 15 the engine is such as to secure various other benefits and advantages, all of which will be pointed out. It is one of the primary objects of my invention that the controlling valves shall have absolute and positive operation so that when once adjusted relative 20 to the movement of the piston of the device they may always be relied upon to effect the intake and exhaust at the proper instants. In the inherent construction of the valve it 25 was my object to overcome all possibilities of leakage as far as possible, to distribute friction as far as possible, and to reduce the wall area which is subjected to heat by reason of contact with the heated gases incident 30 to the operation of the device.

The various purposes of my invention as above expressed are consistent with my object of embodying the various advantages above outlined in a simply constructed and 40 easily assembled device. This feature will, however, become more evident as the description proceeds.

To the end of securing efficient and simple valve operation, I employ a movable valve member which reciprocates in a valve chamber and slides past a port leading into the piston chamber. This valve is operatively connected positively with the piston and the movements are so proportioned, in the 45 preferred and specific embodiment herein shown, that the piston makes four strokes to one of the sliding valve. The more deliberate movement of the valve is very effective in reducing friction and the positive 50 connection between the piston and the valve

is effective in maintaining perfect and efficient service. More specifically the preferred valve of my invention is tubular in form and operates quite in the way of a piston although not to compress or move 60 gases to any appreciable degree. The construction makes it possible for the valves to be placed on opposite sides of the cylinder so that the cylinder head can be cast directly with the cylinder body and, further, so that 65 the spark plug may be disposed directly over the piston, an advantage which will readily prove itself to those skilled in the art.

My invention is embodied in the device shown in the accompanying drawings, in 70 which—

Figure 1 is a cross-sectional view, the section being taken on planes passing through the centers of the valve chambers and the piston chamber,

Fig. 2 is a sectional view, in plan, taken in part on the plane $x-x$ of Fig. 1, and in part on the center line of the gear box so as to disclose the gear relations. The line $y-y$ of this figure indicates the series of planes 80 on which the section shown in Fig. 1 is taken,

Fig. 3 is a side elevational view of the device, two cylinders being shown, it being understood that any number may be employed,

Fig. 4 is a detail view showing the valve construction.

Fig. 5 is a cross-sectional view taken on the plane $5-5$ of Fig. 4, and

Fig. 6 is a further detail view, being a longitudinal section of the valve structure.

Similar reference characters are applied to the same parts throughout the various figures.

In the drawings I have illustrated the body portion of the casing at 10, this body portion comprising the common crank case 11 and the cylinder portions 12, of which there may be any reasonable number. The 100 central part of the body of the casing is bored to form the cylinder 13 which terminates at its upper end in the combustion chamber 14. On opposite sides of this main cylinder 13, the auxiliary cylinders, or valve chambers 15 and 16 are bored, the combustion chamber 14 having the ports 17 and 18 leading to the cylinders 15 and 16, respectively. The main cylinder and the auxiliary cylinders are individually and collec- 110

tively surrounded by a water jacket 19 which is suitably supplied, preferably from the bottom, and relieved by way of the connecting pipes 20, 20 leading to a main outlet 5 pipe 21. The casing 10 is completed by means of the bottom portion 22, which incidentally forms an oil well, and by means of the gear case 23 and the cover 24 therefor, which, in the embodiment herein shown, 10 close the gears employed to operatively connect the piston and the sliding valves which I have heretofore broadly referred to. The parts of the casing may be held together in any suitable manner, the drawings showing 15 the bottom part 22 as held to the body part 10 by means of cap screws 25, 25, and the cover of the gear case being held in place by means of screws 26, 26.

The piston 27 is arranged to reciprocate 20 in the main cylinder 13, this piston being provided with the usual packing rings 28, 28 and with the cross pin 29 to which a pitman rod 30 may be suitably pivoted. This pitman rod is journaled at its other end 25 upon the crank 31 on the main crank shaft 32 which passes lengthwise of the crank chamber 11 and is suitably journaled in the ends thereof, intermediate bearings 33 being provided, if necessary. This main shaft 32 30 passes directly out of the crank case at one end and out of the other end through the gear case 23 in which it has secured thereto a pinion 34. This pinion is of sufficient width to accommodate the overlapping 35 gears 35 and 36, disposed in the gear case, and securely mounted upon the auxiliary crank shafts 37 and 38 respectively. These auxiliary shafts extend the length of the crank case and, for each cylinder, are each 40 provided with a crank 39 upon which a connecting rod 40 is journaled in any suitable manner. By way of these connecting rods 40 the shaft 37 is operatively connected with the tubular valves 41 which are arranged to 45 reciprocate in the cylinders 15, and the shaft 38 is joined to tubular valves 42 arranged to reciprocate in the cylinders 16. It will now be seen that reciprocation of the piston 27 will cause rotation of the main shaft 32 and, 50 by means of the pinion 34 and gears 35 and 36, will effect the reciprocation of both the tubular valves 41 and 42. The ratio and timing of these parts will be taken up fully 55 when the operation of the engine is described.

For purposes of lubrication the bottom part 22 of the casing is provided with a shelf or partition 43 which has the central depression 44 in which the crank 31 is adapted to 60 plunge. This depression is filled with oil and the shaft, as it rotates, will be effective in throwing the oil to lubricate the other parts in immediate proximity. The well at the bottom of the part 22 is kept filled and 65 clean by means of a flow of oil, the shelf 43

being reticulated, as indicated at 45, 45, to provide for proper circulation.

Each of the valve cylinders or chambers 15 and 16 have extending thereinto, from the top thereof, a tube 46 which is held in place by the engagement of a flange 47 at the upper end thereof with a shoulder 48 formed by countersinking the cylinder, the flange being securely held by a convenient pipe coupling 49 which makes connection 70 with the interior of the tube 46 and which is held in place upon the top of the casing by means of the cap screws 50, 50. The pipe 49 passes to a muffler or carburetor, depending upon whether the associated valve 75 is for exhaust or intake. A suitable gasket 51 is interposed between the pipe couplings 49 and the casing for obvious purposes. The tube 46, in the main, fits snugly inside the tubular valve member associated therewith and it is thus that the valve member 80 may well be considered a sleeve operating in an annular slot. The valve sleeve 41 is provided with an opening 52 arranged to pass and connect with the port 17 simultaneously with the openings 53 in the inner tube 46, this opening registering, as clearly shown in Fig. 1, with the port 17. Similarly the valve sleeve 42 is provided with an opening 54 which is arranged to pass and connect with the port 18 simultaneously with the opening 55 in the side of the inner tube 46 associated with this valve, the opening 55 registering with the port 18. The strokes of the sliding valves are such that the ports which they control will be opened and closed for each movement of the valve in each direction. The significance of this 85 operation will be pointed out more fully 90 hereinafter.

In order that the control of the ports of the combustion chamber may be perfect and complete, and in order that leakage may, as much as possible, be avoided, I provide the sliding sleeve valves 41 and 42 with the 95 packing rings 56, 56, these rings being so disposed that at no time, in the movement of the sleeve, do they pass a port. I also provide the inner tubes 46, 46 with the packing rings 57, 57 which also are preferably 100 placed so as not to be passed by the port in the associated sliding valve during the movement thereof. To facilitate lubrication the upper part of the inner tubes 46 are reduced in diameter as indicated at 58, 58 to 105 form a reservoir for oil.

An examination of Fig. 1, particularly, 110 will indicate how this relation of parts, including the casing, the inner tube, and the sleeve valve, is effective in preventing leakage. The path would be so long as to make the leak negligible, while the packing rings 115 will be effective in keeping even this down to a minimum.

The valve construction is shown particu- 120

haust valve open during the explosion stroke of the piston in order that the cylinder may be thoroughly cleansed on high speeds. This may be provided for in several ways, one of 5 the most convenient being to merely shorten the length of the crank to which the valve is connected, to a certain degree, it being apparent that the valve will then pass the opening more slowly. Of course the valve 10 must be adjusted in position relative to the piston so that it will close the port when the piston finishes the exhaust stroke. It is also desirable frequently to have the intake valve remain open during a considerable 15 portion of the compression stroke, for in this way the inertia of the entering gases will fill the combustion chamber and this may be provided for in the same way.

It will be noted that the volume of the 20 gas passages remains at a minimum and that, in the combustion chamber the gases are all collected directly over the piston where they are locally ignited. It is also to be noted that there are no springs or cams 25 and that the valves are always in positive relation to the piston. The size of the openings in the sliding sleeves would determine the length of time during which the associated ports remain open, and it is clear 30 that it is this opening which may conveniently be adjusted to the stroke of the piston. The various parts are simply associated and combined, the staggered arrangement hereinbefore described being particularly useful in securing this result. As to 35 the relative disposition of the parts, I wish to state that I contemplate planing both auxiliary cylinders together on the same side of the associated main cylinder and, in

staggering, to place both on the same side 40 of the center line of the main cylinder, instead of on opposite sides as illustrated in Fig. 2.

I claim as new and desire to secure by 45 Letters Patent:

1. In an explosion engine, a casing having a cylinder and a valve chamber on each side of said cylinder, a valve in each of said valve chambers, a piston operating in said cylinder, and means for operatively connecting said piston and said valves, said valve chambers being offset relative to said cylinder. 50

2. In an explosion engine, a casing having a plurality of aligned cylinders and a valve chamber on each side of each of said cylinders, a valve in each of said valve chambers, a piston operating in said cylinder, and means for operatively connecting said piston and said valves, said valve chambers 55 being staggered relative to said cylinders. 60

3. In an explosion engine, a casing having a cylinder and a valve chamber on each side of said cylinder, a sliding valve in each of said valve chambers, a piston operating 65 in said cylinder, a main crank shaft with which said piston is connected, and auxiliary crank shafts operatively connected with said main crank shaft and said sliding valves, said valve chambers being offset relative to 70 said cylinder.

In witness whereof, I hereunto subscribe my name this 8th day of December, A. D. 1909.

HARRY C. TILLOTSON.
